UNITED STATES PATENT OFFICE.

JOHN A. HEMFLING, OF LESTER PRAIRIE, MINNESOTA.

SHADE AND CURTAIN BRACKET.

1,417,247.

Specification of Letters Patent. Patented May 23, 1922.

Application filed July 17, 1920. Serial No. 397,060.

To all whom it may concern:

Be it known that I, JOHN A. HEMFLING, a citizen of the United States, residing at Lester Prairie, in the county of McLeod and 5 State of Minnesota, have invented certain new and useful Improvements in Shade and Curtain Brackets, of which the following is a specification.

This invention relates to window fixtures, 10 and the primary object of the invention is to provide an improved combined window shade and curtain rod holder so as to eliminate the necessity of providing a separate fixture for holding the curtain and for holding 15 the window shade.

Another prime object of the invention is to provide an improved window shade and curtain holder which can be adjusted to various sized window casings and which will 20 not require any extraneous means for holding the same in position, thereby eliminating the necessity of marring the woodwork by the use of nails, screws, tacks and the like.

25 A further object of the invention is to provide an improved combined window shade and curtain holder embodying a pair of adjustable clamps or jaws arranged to engage the opposite sides of the window casing, the 30 jaws carrying the shade roller support and the curtain rod support.

A still further object of the invention is to provide an improved combined window shade holder and curtain support of the 35 above character, which is durable and efficient in use, one that is simple and easy to manufacture, and one which can be placed upon the market at a reasonable cost.

With these and other objects in view, the 40 invention consists in the novel construction, arrangement and formation of parts as will be hereinafter more specifically described, claimed and illustrated in the accompanying drawings, forming a part of this specification, in which drawings:

Figure 1 is a fragmentary front elevation of the window casing showing the improved combined window shade holder and curtain rod support in operative position thereon.

50 Figure 2 is a plan view of one of the supports.

Figure 3 is an enlarged front elevation of the same.

Figure 4 is an inner end view of the same, and 55

Figure 5 is a detail perspective view of the curtain rod holder carried by the support.

Referring to the drawings in detail, wherein 60 similar reference characters designate corresponding parts throughout the several views, the letter A generally indicates the improved combined curtain rod support and window shade holder, which is adapted to engage the window frame B.

The improved combined window shade holder and curtain rod support comprises a pair of members 10 and 11 which are adapted 65 to be positioned at opposite sides of the window casing as is usual in window shade or curtain supports. Each of the members 10 and 11 includes a section 12 and a section 13. Each of these sections is substantially triangular shaped and the section 12 is provided with a right angularly extending 70 clamping jaw 14 which lies in parallel relation with the right angularly extending clamping jaw 15 formed on the section 13. Each of 75 these jaws 14 and 15 is provided with right angularly extending biting teeth 16 and 17. It can be seen that these biting teeth 16 and 17 are adapted to engage in the opposite 80 faces of the side members of the window casing so as to effectively hold the members 10 and 11 in operative position in relation 85 to each other. The section 12 of each one of the members 10 and 11 includes the inwardly extending cylindrical rod 18 which is adapted to extend through the opening formed in the foot 19 formed on the inner 90 end of the section 13. The right angularly extending jaw 15 formed on the section 13 is also provided with an aperture which is formed in direct alignment with the aperture formed in the foot 19 and the portion 95 of the rod 18 which is adapted to extend through the aperture formed in the jaw 15 is threaded as at 20 and a winged nut 21 is adapted to be threaded on the rod so as to bring the jaws 14 and 15 toward or away 100 from each other and thus permit of the adjustment of the same in relation to the width of the side pieces of the window frame B. The section 13 has the lower edge of the jaw 15 thereof provided with an integral 105 depending extension 22 and this extension is

provided with an upstanding vertically disposed plate 23. This plate 23 has its upper end provided with the usual opening 24 for the reception of the spindle formed on the 5 terminals of the window shade roller, and it is to be understood that one of these members 23 is provided with the usual recess for receiving the cylindrical spindle formed on the window shade roller and the other provided with the slot provided for the reception of the polygonal shaped stud formed on the opposite end of the window shade roller. It can be seen that these plates 23 extends inwardly from the side members of the 15 window casing and are adapted to support the ordinary window shade designated by the letter C. It also can be seen that where there is a slight difference in the width of the window shade, the plates 23 may be 20 forced toward or away from each other to make up this slight difference.

Each of the sections 12 of the members 10 and 11 are provided at its upper and lower terminals with aligned eyes 26 and these 25 aligned eyes 26 are adapted to receive a curtain pole supporting rod 27. The rods 27 are adapted to support the usual or any preferred type of curtain pole designated by the letter D. Each of these rods 27 as 30 shown includes a vertically disposed body portion 28 and the right angularly disposed terminal 29 which is adapted to form a hook for the reception of a terminal of the curtain supporting pole D. The lower end of 35 the body portion 28 of the curtain pole holder 27, is provided with a right angular portion 30 and a depending extension 31 which is adapted to fit in the aligned eyes 26. The upper eye 26 has its upper surface 40 provided with a notch 32 in which is adapted to fit the right angularly extending portion 30, and the provision of this notch prevents the turning movement of the rod 28 for the curtain pole and the eye.

45 In applying the improved combined window shade and curtain bracket to a window casing it is merely necessary to place the sections 12 and 13 on the window casing adjacent to the upper ends thereof and 50 tighten the wing nut 21 on the threaded portion 20 of the rod 18. This will effectively bring the jaws 14 and 15 into tight engagement with the opposite faces of the side pieces of the window casing which will 55 force the biting teeth 16 and 17 into the window casing. If necessary the jaws 14 and 15 may be given a slight tap so as to further force the biting teeth into biting engagement with the window casing. The 60 provision of the plates 23 extending inwardly of the inner sections 13 of the members 10 and 11 permits the easy placing of the window shade on a window and elimi-

nates the hiding of a portion of the window casing which is usual in the ordinary type 65 of shade bracket now employed. The means employed for connecting the rods 27 for the curtain pole is also a novel arrangement and it can be seen that the curtain pole will be effectively supported above the window 70 shade roller which is desirable.

Changes in details may be made without departing from the spirit or scope of this invention; but,

I claim:

1. A window shade and curtain pole bracket comprising a pair of independent plates, the outer edges of said plates being provided respectively with right angularly extending jaws arranged to engage the opposite side faces of the side piece of a window casing, an inwardly extending rigid rod carried by the outer plate, the inner plate having aligned openings for slidably receiving the rod, the inner end of said rod 85 being threaded, an adjusting nut threaded on said rod, vertically aligned eyes carried on the outer plate, a curtain pole supporting rod arranged to be detachably fitted in said eyes and including a body portion and 90 a right angularly extending foot, the upper eye having a notch formed therein arranged to receive said foot, and a hook member formed on the upper terminal of the rod, the inner plate having a vertically disposed 95 extension formed thereon and provided with means for the reception of the pintle of a shade roller.

2. In a combined window shade and curtain pole supporting bracket, a pair of triangular shaped sections, right angularly extending jaws formed on the base portions of the sections, inwardly extending biting teeth formed on the outer edges of the jaws, an inwardly extending rod formed on the apex 100 portion of one of the sections, a right angularly extending foot formed on the apex portion of the other section, the right angularly extending foot and jaw of the last 105 mentioned section having aligned openings 110 therein arranged to slidably receive the rod, the outer end of said rod being threaded, a winged nut fitted on said rod arranged to frictionally engage the last mentioned section, a depending resilient bendable plate 115 formed on the lower edge of the jaw of the last mentioned section, a vertically disposed extension formed on said bendable plate provided with means for the reception of a pintle of a window shade roller, the other 120 section having vertically aligned eyes formed therein, and a curtain pole supporting rod detachably fitted in said aligned eyes.

JOHN A. HEMFLING.
